MEDICAL EXAMINATION DRAPE

Phyllis Irene Djourup, Yonkers, N. Y.

Application January 27, 1950, Serial No. 140,795

3 Claims. (Cl. 2—114)

1

This invention relates to a drape for covering patients during medical examinations in general, and more particularly, during examinations involving the pelvic region.

It is the custom in the medical profession to provide a cover for the patient whenever any general examination is given. The purpose of the cover is partly to protect the patient from temperature changes, but more particularly to overcome the sensitivity of patients with regard to exposure of person, and thus help the patient relax to facilitate the examination, particularly in gynecological and proctological examinations. Especially when more than one sex is present or the patient is a female, it is the custom to cover the patient and to expose only the portion of the body which is being examined.

Various constructions of cover have been used, including shirts open at the side, boot-like garments, and the like. Perhaps the most commonly used cover is an ordinary bed sheet or crib sheet. This type of cover has been in wide use because it can be adapted to physical examinations in general. It also has the advantages of ease in laundering, compactness in storing, and relative inexpensiveness. However, the bed sheet has disadvantages. It has always been a problem to adjust a plain rectangular sheet so it will cover the patient and remain in position, and yet facilitate exposing limited areas of the person as examination proceeds.

A bed sheet is particularly unsatisfactory for gynecological and proctological examinations.

The bed sheet is not adapted to facilitate the limited exposures desirable without uncovering additional areas or dislocating the entire sheet. It is awkward and time consuming to arrange, and is embarrassing to the patient if it doesn't remain in place. It takes a trained person to arrange such a sheet and the sheet needs constant adjusting as the examination proceeds from one point to another. Arranging the sheet is a skilled, time consuming operation which takes an undue amount of time of the nurse or doctor. The operation is too complicated to be done satisfactorily by the patient herself.

A drape made in accordance with my invention can be used for all forms of complete medical examinations, and is particularly useful in gynecological and proctological examinations. The medical drape which I have invented is adapted to be placed by the patient herself to maintain its position as the examination proceeds and to facilitate the exposure of only limited portions of the body at a time.

2

It is characteristic of my invention that it comprises a sheet having three branches along its lower edge, and a pocket in the end of each outer branch to receive the patient's toes. The central branch between the two outer branches forms a free central flap that may be lowered to cover those portions of the patient's body between the legs, or may be raised to permit examination.

10 It overcomes the long-felt disadvantages of the plain sheet. At the same time, it is as easy to launder as a plain sheet, and requires no more storage space than a plain sheet. The operations of manufacturing it are simple, so that the cost of making it is not great.

The accompanying drawings which form part of the application illustrate the invention by way of example:

Figure 1 is a front plan view of a drape embodying the invention;

Figure 2 is a rear plan view of a drape similar to that shown in Fig. 1, but showing a modification;

Figure 3 is a figure similar to Fig. 1, but showing the outer branches of the drape fastened together and the central flap raised;

Figure 4 is a longitudinal section on the line 4—4 of Fig. 1;

Figure 5 is a perspective view of the front of the drape, covering a patient, prone upon an examination table in a lithotomy position;

Figure 6 is a perspective view of the front of the drape with the outer branches fastened together as in Fig. 3, and covering a patient in knee-chest position for a proctological examination;

Figure 7 is a plan view of a blank from which drapes illustrated in Figs. 1 to 4 may be made.

The novel drape 10 comprises a substantially rectangular sheet having three branches at one end, namely a pair of outer branches 11 with a pocket 12 at the end of each and a central branch or flap 13 between the two outer branches. The three branches are free from each other for purposes which will be explained below. Fastening means 14 and 15 are provided at the inner edges of the outer branches near, but spaced from the top thereof, to fasten the two outer branches together.

If desired, an outlet for the arms of the patient can be provided, as for example, curved slits indicated by lines at 16 in Fig. 2 forming shoulders 17. If desired, a neck opening may also be provided as indicated in dotted lines at 18 in Fig. 2.

55 The drape is preferably of a size to sub-

3

stantially cover the body of an adult person, and the branches at the lower end are substantially the length of the legs of a human body up to about the hipbone. The drape is preferably sufficient in width so that the side branches not only lie on top of the legs of the patient, but hang down over them on the sides to completely cover the legs. But the dimensions need not be exact. A drape which will accommodate a tall, broad person can be used satisfactorily for a small person.

In using the drape, the patient slips the toes into the pockets 12 and pulls the upper end 19 of the drape up over the body. The drape is equally well adapted to cover the front or the posterior of the patient's body.

For example, if the patient is to assume a position in which she lies on her back, thighs and legs flexed and knees wide apart, as shown in Fig. 5, the patient slips a foot into each pocket with the soles of the feet toward the back 20 of the pocket, and pulls the top of the drape up over the front of the body. The two outer branches 11 will cover the legs of the patient and the central branch will cover the portion of the body between the legs while the upper part 19 of the drape will cover the torso and arms.

When the doctor is ready to make a gynecological examination, it is only necessary for the nurse to raise the flap or central portion 13, whereupon the part of the body to be examined will be exposed and all the rest of the patient's body will remain covered.

When it is desired to examine the patient in the knee-chest position, as shown for example in Fig. 6, the fastening means 14, 15 may first be connected together as shown in Fig. 3. The patient then puts the drape over her back, and slips a foot into each pocket 12 with the soles of the feet toward the front of the pocket, and assumes the desired position. Before the examination, the central branch or flap 13 will be down as shown in dotted lines in Fig. 3. When the doctor is ready to make a proctological or a gynecological examination, the flap 13 is raised disclosing only the part to be examined.

The toe pockets at the end of the outer branches of the drape simplify the placement of the drape and also retain the drape in position as the examination proceeds. In the embodiment illustrated in the drawings, the toe pockets are wide at the top and narrower at the bottom. This makes it easy for the patient to guide her feet into them. Putting the feet in the pocket and pulling the top of the sheet toward the head of the patient automatically adjusts the drape both longitudinally and laterally on the body of the patient.

If a doctor wishes to examine a leg, it is very simple for the patient to slip her toes out of the pocket and then return the feet to the pocket when the examination of that leg has been finished.

When used for a general examination, the upper half of the drape is moved about for a chest or other examination of the upper body. After each step of the examination, the patient can be immediately aware that the drape is replaced in its proper position merely by pulling the top up to her shoulders, keeping her toes in the pockets.

If arm outlets are provided as indicated in Fig. 2, the patient's arm can be put through the arm outlet 16, so that the shoulder 17 of the drape rests upon the arm or shoulder of the patient. This is an added aid in automatically adjusting the position of the drape, and in keep-

4

ing the drape in position, especially when the patient is standing or sitting.

The embodiment of the invention shown in the drawings can be made as follows:

A blank of the proper dimensions, such as shown in Fig. 7, is slit longitudinally at two points A, A' along the lower end to form the slits AB and A'B.

A blank about 64 inches wide and about 72 inches long is large enough to cover most patients. The slits AB and A'B' can be about 25 inches from the outer edges of the blank leaving a flap of about 14 inches wide between the slits. The slits AB and A'B' can suitably be about 30 inches long. One end of the blank has now been slit into three parts, the outer parts forming the branches 11 of the drape and the central part forming the flap 13 of the drape. At the end of each outer branch the corners are now brought together, for example, point A is brought to point D so that AC rests on DC. Ends of its two halves AC and DC are secured together as by stitching, to form the pocket 12, as shown in Figs. 1 to 4.

The cut edges of the drape can be finished in any suitable manner, such as hemming, binding or facing. Cooperating fastening means 14 and 15 respectively are now secured adjacent the insides of the flaps 11 and they can suitably be placed about 5 inches below the top of the dividing lines AB and A'B' respectively.

A drape having the dimensions given in the above example will be suitable for most adult patients. It will be noted that the width of the central flap 13 is considerably wider than the width of that part of the human body, sometimes referred to as the crotch, which lies between the upper inner legs, regardless of the position of the knees. The dimensions given above are by way of example. Drapes having different proportions can be used.

If a longer drape is desired, the blank can be of any desired length.

If it is preferred to cover the upper portion of the patient's body with some other garment, as for example the usual hip length hospital gown, the user may prefer to make my medical drape of a shorter length.

The drape can be made of any suitable, non-transparent, drapable material, such as woven or knitted textile fabric, plastic, rubber, or paper.

Other embodiments within the scope of my invention will occur to those skilled in the art.

I claim:

1. A medical examination drape comprising a sheet having three free branches along its bottom edge including two outer branches having toe pockets at their lower ends and a central branch between said outer branches, in combination with complementary fastening means on the two outer branches a short distance below the points where the branches join the rest of the sheet and located at the inner edges of said branches whereby the area of the patient uncovered by lifting the central branch is limited to a short distance below the point where the branches join the rest of the sheet.

2. A medical examination drape comprising a sheet having three free branches along its bottom edge including two outer branches having toe pockets at their lower ends and a central branch between said outer branches, having arm outlets at the upper end, whereby a patient's toes in the pockets, and arms in the arm outlets adjust the drape in position covering the patient's

body, and the central branch is free to permit exposure of only limited areas of the body for examination.

3. A medical examination drape of a size to substantially cover a human body comprising a sheet whose lower portion is divided into three free branches extending from the lower end for a distance substantially as long as the length of a leg of said body in combination with toe-receiving pockets on the ends of the two outside branches. 10
